UNITED STATES PATENT OFFICE

121,501

DESIGN FOR A DESK THERMOMETER

Ralph C. Wappner, Springfield, Ohio, assignor to
The Ohio Thermometer Company, Springfield,
Ohio, a corporation of Ohio

Application March 5, 1940, Serial No. 90,700

Term of patent 7 years

To all whom it may concern:

Be it known that I, Ralph C. Wappner, a citizen of the United States, residing at Springfield, in the county of Clark and State of Ohio, have invented a new, original, and ornamental Design for a Desk Thermometer, of which the following as a specification, reference being had to the accompanying drawing, forming part thereof.

Fig. 1 is a perspective view, Fig. 2 a side elevation and Fig. 3 a rear elevation of a desk thermometer, showing my new design.

The design comprises a base, both sides of which slope inwardly toward the rear and also

slope in an upward direction by steps, with the upper edge of each step formed on a curve. The forward end of the base has a reduced projection, the forward portion of which is inclined rearwardly from bottom to top. A thermometer tube extends from the forward portion of the base, but at the rear of the forward projection thereon, at a rearward inclination.

I claim:

The ornamental design for a desk thermometer, as shown and described.

RALPH C. WAPPNER.
